CLAIM

The ornamental design for a combined animal carrier and litter box, as shown and described.

DESCRIPTION

FIG. 1 is a front perspective view of a combined pet carrier and litter box;

FIG. 2 is a front elevational view thereof;

FIG. 3 is a rear view thereof;

FIG. 4 is a left-side elevational view thereof; the right-side being a mirror image of the left side;

FIG. 5 is a top plan view thereof; and,

FIG. 6 is an exploded front perspective view thereof with the handle and latch in raised positions.
